GUSTAV DÜSTERLOH, OF SPROCKHÖVEL, GERMANY.

AERIAL VESSEL.

1,020,484.

Specification of Letters Patent. Patented Mar. 19, 1912.

Application filed October 11, 1910. Serial No. 586,467.

To all whom it may concern:

Be it known that I, GUSTAV DÜSTERLOH, engineer, subject of the German Emperor, residing at Sprockhövel, Westphalia, Germany, have invented a new and useful Aerial Vessel; and I do hereby declare the following to be a full, clear, and exact description of the same.

This invention relates to aerial vessels of the dirigible type.

The improved vessel is of low air-resistance, and can easily be taken to pieces, stowed in small compass for transport and quickly reassembled. The invention also allows of the construction of aerial vessels of greater size as desired from the same elementary parts. In case of damage to single units or sections of the aerostat body, the latter remains fit for use and the damaged elements can be easily and quickly exchanged for new ones, which if desired can be forwarded at once in the inflated condition. This technical advantage is obtained essentially by constituting the vessel of a number of balloon-sections resembling life-buoys, in such a way that a continuous channel is formed in the direction of the length of the vessel.

The accompanying drawing represents by way of example a form of construction of the improved vessel.

Figure 1 is a front elevation of the vessel and Fig. 2 is a longitudinal section. Figs. 3 and 4 represent front and sectional views respectively of a ring-shaped section or balloonet. Fig. 5 shows one of the reinforcing rings, Fig. 5^a a diagrammatic sectional view of one of said rings. Fig. 6 represents the engine room and car.

The aerostat or balloon body A is composed of a number of ring-shaped balloon parts or balloonets 1 to 12, as seen in Fig. 2. The external peripheries of the balloonets form the exterior casing or hull of the vessel, while their inner peripheries form a central longitudinal channel C. The channel C and the cylindrical outer casing of the pipe-shaped aerostat are covered with a suitable smooth sheath or skin D, which reduces the air-resistance and renders the aerostat more stable.

The stability of the aerostat is obtained by means of a central bar E extending through and projecting at both ends of the aerostat and being stayed thereto. The stability is further increased by reinforcing

rings F, F', F^a, F^b which are inserted between the single balloonets and stayed to the bar E. Fig. 5 shows by way of example the construction of one of these truss-rings, 60 which consists of a hub and two rings of wood or metal, which are stayed together and braced in the manner of a cycle wheel.

The balloonets 1 to 12 are of the shape of a life-buoy and are each provided with an inflation valve G and a release valve H (Figs. 3 and 4). The size of the balloonet depends upon that of the airship and the purpose for which it is employed; the external diameter must be in proportion to the 70 internal diameter in order that the air-resistance may not be too great, while on the other hand both the passage channel and the load-capacity above all must not be too small.

Fig. 6 shows the rigid engine-room which consists of a central tube B with the propeller or fan J and the casing K with the car L. The driving motor M is arranged upon the bottom of the casing K, while the 80 navigator may take his seat in the car L. The passengers can be accommodated on both sides of the engine room as well as in the car L. The ring-shaped balloon-sections allow the construction of rigid, semi-rigid or 85 non-rigid aerostats or balloon bodies. The airship can be easily demounted and closed or folded up so that it can be disposed in a small compass and conveniently transported by railway or wagon. Moreover, the individual annular balloonets may also be arranged for forwarding in an inflated condition if desired so that for example the necessary number of spare balloonets can be kept in stock at the depot or again balloonets requiring inflation can be despatched to a distant gas-works for filling. The airship can also be easily arranged for longer or shorter voyages and for heavier or lighter loads by employing a greater or smaller number of 90 95 these annular balloonets according to the purpose and particular requirement. An injury to any one balloonet is therefore not a serious matter because it is of no great importance considering the large number of 100 them; on the other hand the damaged balloonet can easily be replaced. The engine-room may remain open at the top for the taking of astronomical observations and bearings, or gas bags can be provided above the 105 engine room as shown in Fig. 2. To further increase the stability, each single balloonet

- may be stayed in such a way that the ties or stays form in the center a small circular opening by means of which the ballonnet is fitted upon the central bar E. With the object of accelerating the erection and taking down of the body, larger units for example of three ballonets complete can be supplied, so that they can be provided with common external and internal sheaths or envelops D 10 which after fitting the unit upon the central bar F have only to be buttoned or clipped to the corresponding sheaths of the preceding unit or secured to the truss-ring F which is inserted between every two units. For larger vessels a number of tubular bodies 15 lying beside and above one another may be formed from the ballonets.
- Having now particularly described and ascertained the nature of my said invention 20 and in what manner the same is to be performed, I declare that what I claim is:—
1. An aerial vessel consisting of a central bar, a plurality of separated ballonets made of soft material and in life-buoy shape and arranged upon said central bar so that a continuous channel exists in the direction of the length of the vessel; means for driving the vessel and means for carrying passengers by the vessel.
  2. An aerial vessel consisting of a central bar, a plurality of separated ballonets made of soft material and in life-buoy shape and arranged upon said central bar so that a continuous channel exists in the direction of the length of the vessel; a smooth sheath covering said ballonets; means for driving the vessel; and means for carrying passengers by the vessel.
  3. An aerial vessel consisting of a central bar, a plurality of separated ballonets made of soft material and in life-buoy shape and arranged upon said central bar so that a continuous channel exists in the direction of the length of the vessel; truss-rings between said ballonets braced in the manner of a cycle wheel and fitted upon said central bar; means for carrying passengers by the vessel; and means for driving the vessel.
  4. An aerial vessel consisting of a central bar, a plurality of separated ballonets made of soft material and in life-buoy shape and arranged upon said central bar so that a continuous channel exists in the direction of the length of the vessel; a smooth sheath covering said ballonets; truss-rings between said ballonets braced in the manner of a cycle wheel and fitted upon said central bar; means for driving the vessel; and means for carrying passengers by the vessel.
  5. An aerial vessel consisting of a central bar, a plurality of separated ballonets made of soft material and in life-buoy shape and arranged upon said central bar so that a continuous channel exists in the direction of the length of the vessel; a propeller; an engine for driving said propeller; a rigid engine-room inserted between said ballonets; and means for carrying passengers by the vessel for driving said propeller; a rigid engine-room inserted between said ballonets; and means for carrying passengers by the vessel.
6. An aerial vessel consisting of a central bar, a plurality of separated ballonets made of soft material and in life-buoy shape and arranged upon said central bar so that a continuous channel exists in the direction of the length of the vessel; a smooth sheath covering said ballonets; a propeller; an engine for driving said propeller; a rigid engine-room inserted between said ballonets; and means for carrying passengers by the vessel.
7. An aerial vessel consisting of a central bar, a plurality of separated ballonets made of soft material and in life-buoy shape and arranged upon said central bar so that a continuous channel exists in the direction of the lengths of the vessel; truss-rings between said ballonets braced in the manner of a cycle wheel and fitted upon said central bar; a propeller; a rigid engine-room inserted between said ballonets; and means for carrying passengers by the vessel.
8. An aerial vessel consisting of a central bar, a plurality of separated ballonets made of soft material and in life-buoy shape and arranged upon said central bar so that a continuous channel exists in the direction of the length of the vessel; a smooth sheath covering said ballonets; truss-rings between said ballonets braced in the manner of a cycle wheel and fitted upon said central bar; a propeller; an engine for driving said propeller; a rigid engine-room inserted between said ballonets; and means for carrying passengers by the vessel.
9. An aerial vessel consisting of a central bar, a plurality of separated ballonets made of soft material and in life-buoy shape and arranged upon said central bar so that a continuous channel exists in the direction of the length of the vessel; a propeller; an engine for driving said propeller; a rigid engine-room inserted between said ballonets; and a car supported by said engine-room.
10. An aerial vessel consisting of a central bar, a plurality of separated ballonets made of soft material and in life-buoy shape and arranged upon said central bar so that a continuous channel exists in the direction of the length of the vessel; a smooth sheath covering said ballonets; a propeller; an engine for driving said propeller, a rigid engine-room inserted between said ballonets; and a car supported by said engine-room.
11. An aerial vessel consisting of a central bar, a plurality of separated ballonets made of soft material and in life-buoy shape and arranged upon said central bar so that a continuous channel exists in the direction of the length of the vessel; truss-rings between said ballonets braced in the manner of a

cycle wheel and fitted upon said central bar; a propeller; an engine for driving said propeller; a rigid engine-room inserted between said ballonnets; and a car supported by said engine-room.

12. An aerial vessel consisting of a central bar, a plurality of separated ballonnets made of soft material and in life-buoy shape and arranged upon said central bar so that a continuous channel exists in the direction of the length of the vessel; a smooth sheath covering said ballonnets; truss-rings between said ballonnets braced in the manner of a

cycle wheel and fitted upon said central bar; a propeller; an engine for driving said propeller; a rigid engine-room inserted between said ballonnets; and a car supported by said engine-room.

In testimony whereof, I have signed my name to this specification in the presence of two subscribing witnesses.
